CLAIM

The ornamental design for a magnifier with lamp, as shown and described.

DESCRIPTION

FIG. 1 is a perspective view of a magnifier with lamp showing my new design;

FIG. 2 is a front elevational view;

FIG. 3 is a rear elevational view;

FIG. 4 is a right side elevational view thereof, the left side elevational view being a mirror image thereof;

FIG. 5 is a top plan view;

FIG. 6 is a bottom plan view;

FIG. 7 is an elevational view thereof showing that one stand is set up and the other is collapsed; and,

FIG. 8 is another elevational view thereof showing that the two stands are both set up thereof.
